UNITED STATES PATENT OFFICE.

CHARLES L. KING, OF MONTAGUE, MICHIGAN.

SHIPPING-PACKAGE.

SPECIFICATION forming part of Letters Patent No. 469,744, dated March 1, 1892.

Application filed September 10, 1891. Serial No. 405,347. (No model.)

To all whom it may concern:

Be it known that I, CHARLES L. KING, a citizen of the United States, residing at Montague, in the county of Muskegon and State 5 of Michigan, have invented certain new and useful Improvements in Shipping-Packages, of which the following is a specification.

My invention relates to improvements in packages for shipping merchandise which 10 need to be strong, light, and cheap, but are not necessarily very tight; and the objects of my improvements are, first, to provide a strong, neat, light, and cheap package that can be utilized for another use after it has served as 15 a package for the transport of goods, and, second, to furnish a package that can be nested for shipment in the knockdown and quickly and easily be formed again into a shipping-case. I attain these objects by the formation 20 of the case illustrated in the accompanying drawings, in which—

Figure 1 is a side view of the completed package as it appears when filled and ready for shipment. Fig. 2 is an end view of the 25 same, showing the hand-holes in the two sections of the case and the means of fastening the two sections together to make a complete case by means of connecting a suitable fastener through these hand-holes. The bracing- 30 stays are also shown in this view. Fig. 3 is a top view of the two halves of the case shown as filled with wooden butter-plates ready to be joined for shipment. This view also illustrates the appearance of the case 35 when opened at its point of destination.

Similar letters of reference indicate like parts throughout the several views.

My improved case is formed of two similar parts, the bottom and the top, and as these 40 parts are alike it follows that the line of juncture in the completed case is in its center longitudinally. As one of the objects of my invention is to furnish a case which shall be useful in its knockdown state after it has 45 served the purpose of a shipping-case, I prefer to form the two halves of the case in such a form that they will be useful as "delivery-baskets" by grocers and others, and hence prefer to form them in the manner here de- 50 scribed—to wit, for the top and bottom halves of the case, which are duplicates of each

other, the baskets A and B are formed as splint or veneer baskets are usually made. The bracing-stays C C are then firmly fastened with tacks, staples, or other devices to 55 the outside of baskets A and B in substantially the position here described—to wit, begin near each end of hand-hole D and fasten with tacks between the two top stay-hoops of the basket one end of each of the 60 two bracing-stays C C, then spread apart the stays, so that they reach the outside corners of the basket at the bottom, continuing along the bottom, near the corners, fastening as applied, and to the other end in the 65 same manner and position as the first end. This application of the bracing-stays brings their ends close together at the rim of the baskets, and as they diverge toward the bottoms they thereby furnish a brace against 70 the collapsing of the ends of the case as a whole should several packages be piled one upon the other.

I prefer to form the baskets smaller at the bottom than at the top, so that they will nest 75 for shipment and then can be easily taken apart and put together for use to make the complete case. The two separate halves A and B, after being filled with the goods they are to carry, are united together at their top 80 edges, in which position they are fastened by looping the metal strip E around the top rims of the baskets through the hand-holes D D, where it is fastened in place by the tack F or other similar device. 85

My improved package is especially adapted to the shipment of wooden butter-plates, as such grocerymen and others as usually buy and use butter-plates of this sort are also users of delivery-baskets of the kind here de- 90 scribed. As such baskets are bulky to ship, they are quite expensive when they reach the consumer or user. My improved case is especially designed to be made by the maker of veneer butter-plates, and can be made as 95 cheaply, or nearly so, as the common crate now in use for the shipment of such butter-plates, and which has no value after use, and as the case is filled with goods in transit the freight charges upon it alone are nominal. I 100 do not wish to limit myself to the use of my improved case for the shipment of wooden

butter-plates alone. Other similar articles might be carried by it safely and well, as it is light, strong, and cheap, and by being made, as here described, so that the separate halves 5 will "nest" it can be shipped as are packing-boxes in the "knockdown" and at its place of destination quickly assembled as a shipping-case.

I am aware that baskets similar in some respects to those I here show and describe, are old, and I do not claim them, broadly; but I do not know nor do I believe that prior to my invention two baskets combined with each other, each provided with the bracing-stays 15 C C, the hand-holds D D, and fasteners E E, have ever been known or used.

What I claim as my invention, and desire to secure by Letters Patent, is—

1. The combination, in a shipping-case, of 20 the baskets A A, each provided with the bracing-stays C C, severally fastened at one end near each end of the hand-hole D, thence spread apart toward the outside corners of the basket at the bottom, continuing along the bottom of the basket and up the other end in 25 like manner as at the end where first applied,

said bracing-stays being fastened to the basket at intervals along their length, the hand-holes D D, and a fastening device for uniting the two baskets together at the hand-holes, 30 thereby forming a shipping-case, substantially as described.

2. The combination, in a shipping-case, of the baskets A A, each of which is sufficiently smaller at the bottom than the top to enable 35 them to be nested and each provided with the bracing-stays C C, severally fastened at one end near each end of the hand-hole D, thence spread apart toward the outside corners of the basket at the bottom, continuing 40 along the bottom of the basket and up the other end in like manner as at the end where first applied, said bracing-stays being fastened to the basket at intervals along their length, the hand-holes D D, and a fastening 45 device for uniting the two baskets together at the hand-holes, thereby forming a shipping-case, substantially as shown.
